UNITED STATES PATENT OFFICE.

JAMES C. DAWSON, OF WEBSTER GROVES, MISSOURI.

LEDGER.

1,383,537.

Specification of Letters Patent.

Patented July 5, 1921.

Application filed May 5, 1919. Serial No. 294,768.

To all whom it may concern:

Be it known that I, JAMES C. DAWSON, a citizen of the United States, and resident of Webster Groves, county of St. Louis, and State of Missouri, have invented certain new and useful Improvements in Ledgers, of which the following is a specification, and which are illustrated in the accompanying drawings, forming a part thereof.

10 The invention relates to loose-leaf ledgers and more particularly to those known as shiftable sheet ledgers and having provision for holding the sheets in either one of two positions. An object of the invention is to 15 provide a ledger which is constructed to facilitate the manipulation of its sheets or pages for machine book-keeping, especially with that style or type of book-keeping machines which require the separate removal 20 of the sheets from the binder for the making of entries upon the sheets and when the sheets upon which entries have been made are to be extended beyond the edges of the 25 remaining sheets at one side to render them more readily accessible for future reference, as in proving the balance at the end of the day.

In the accompanying drawings,

Figure 1 is a perspective view showing 30 one form of the improved ledger with its parts in closed position.

Fig. 2 is similar to Fig. 1 but shows the ledger with the parts positioned for the return of the shifted sheets.

35 Fig. 3 is a side elevation with some of the parts broken away showing the ledger supported in a stand or rack and with the parts in position to permit the manipulation of the sheets incident to the making of 40 entries upon the sheets by machine and returning the sheets to the binder in shifted position.

Fig. 4 is a sectional view taken on the line 4-4 of Fig. 3.

45 Fig. 5 is a plan view of the ledger with some of the parts broken away to show the construction of a locking mechanism.

Fig. 6 is a sectional view taken on the line 6-6 of Fig. 5.

50 Fig. 7 is similar to Fig. 6 but shows a modified form of construction.

Fig. 8 is a detail plan sectional view taken on the line 8-8 of Fig. 6, and

55 Fig. 9 is a perspective view showing one form of the ledger post.

The improved ledger will usually be con-

structed with front and back covers, as 10 and 11, and with a plurality of filing posts, as 12-13, for engaging the sheets, as 14. In the constructions shown, each of the 60 covers 10 and 11 is hingedly connected along one edge to a binding member 15 or 16 and one of these binding members, as 16, carries the filing posts 12-13 while the other binding member, as 15, is formed with apertures 17-18 through the same to permit of its application to the posts 12-13 over the 65 sheets 14 in a well known manner.

When the shifting of the sheets 14 is to be permitted each sheet is preferably formed 70 with slotted filing apertures, as 19-20. Apertures of this form allow the return of the sheets, after shifting, without disengagement from the posts 12-13. A third post, as 21, serves for holding the sheets 14 in 75 either one of two positions. As shown, the post 21 is located beyond the post 13, and at such a distance from it that it may enter one of the slotted apertures, as 21, of any sheet with the post 13 or it may engage the 80 side edge of the sheet adjacent the said slotted aperture. For convenience in permitting the manipulations of the sheets the post 21 is carried by the binding member 15. The two filing posts 12-13 and the 85 post 21 accordingly enter the sheets from opposite directions. When the parts are arranged in this manner, the post 21 preferably does not project through the binding member 16 at any time but this binding 90 member merely has a socket, as 22, upon its inside face for receiving the end of the post 21. As all of the posts 12, 13 and 21 are desirably made of substantially the same length, it follows that the base of the post 95 21 projects outwardly from the binding member 15, in any closed position of the ledger, except when the binding members 15-16 are separated to the greatest extent permitted by the length of the posts 12-100 and 13.

The removal and the return of the sheets 14, incident to the making of machine entries, is most conveniently accomplished when the parts of the ledger are supported 105 in a rack or stand, generally designated 23. As shown, this rack comprises a base plate 24, a pair of sloping oppositely facing uprights 25-26 and side and intermediate guides 27-28 and 29-30. In use, the 110 ledger is placed in the rack 23 with the binding members 15-16 resting upon the inter-

mediate guides 29—30 between the side guides 27—28. The ledger being opened, the sloping uprights 25 and 26 provide rests for the front and back covers 10 and 11. The 5 sheets may thus be readily transferred from a position in which they rest against one of the covers, as 11, to a position in which they rest against the other cover, as 10. In this movement of the sheets the intermediate 10 guides 29—30 serve as guides for the lower edges of the sheets while one of the side guides 27—28 serves as a guide for the adjacent edge of the sheet depending upon whether the sheet is to be placed against the 15 cover 10 in position for the engagement of the post 21 with the edge of the sheet or with the aperture 20. As it is desirable that the side guides 27, 28 should extend over the ends of the binding members 15—16, these 20 binding members are preferably made only of such length as to extend to the limits of the pile of sheets at each side when some of the sheets occupy each of the two positions, as in Fig. 2. As shown, the covers 10 and 25 11 are flush with the ends of the binding members 15—16 at one side, but project beyond the ends of the binding members at the other side, as at 56 (Fig. 1).

The above described manipulation of the 30 sheets 14 is greatly facilitated if each of the posts, as 12—13, and 21, is slidingly mounted in the binding member 16 or 15 by which it is carried. When so mounted the posts 35 may be withdrawn from the sheets prior to the manipulation. It is then unnecessary to thread the sheets over the posts either in removing them from between the covers or in transferring them from a position in which they rest against one of the covers, as 40 11, to a position in which they rest against the cover, as 10.

Preferably each of the posts 12, 13 and 21 is formed with an enlarged base 31 and the 45 two binding members 15 and 16 take the form of flattened metal tubes. In the form of construction which is more particularly illustrated in Figs. 1, 2, 5, 6, 8, and 9, each of the posts 12, 13 and 21 is also provided with a longitudinal slot 32 at one side which 50 does not extend completely to the upper end or head of the post. Under these circumstances the sliding movement of the post in the binding member 15 or 16 which carries the post, may be limited by mounting a 55 spring detent 33 within the chamber of the binding member, the said detent being provided with a projection 34 for entering the slot 32 of the post. The spring detent 33 also serves to provide frictional resistance 60 to the sliding movement of the post in the corresponding binding member.

As shown, the spring detent 33 is constructed in two substantially duplicate parts which parts are urged apart and into contact with posts 12, 13, by a coiled spring 33'

mounted on a pin 33". Pin 33" is preferably carried by one part of detent 33 and freely slidable with respect to the other part. A detent for post 21 is shown in the form of a block 330 pressed into contact with the 70 post by a spring as 331 reacting against the interior of the end of the binding member 15. Block 330 is preferably also provided with a projection 34 in the same manner as are the ends of detent 33. 75

In the form of construction illustrated in Fig. 7, the posts, as 35, 36 and 37, are each formed with an annular groove 38 adjacent one end whereby a shoulder 39 is provided just under the tip, as 40, of the post. When 80 this form of construction is employed the sliding movement of each post in the corresponding binding member, as 16 or 15, may be limited by mounting an apertured sliding plate, as 41 or 42, within the chamber of the 85 said binding member. In this instance the post, 35 or 36, slides through an aperture of the plate 41 or 42 and a spring, as 43, reacts upon the apertured plate to provide frictional resistance against the sliding movement of the post at all times and to insure the engagement of the plate with the shoulder 39 when the post has been withdrawn through a sufficient distance to bring the groove 38 into alignment with the plate. As 90 shown, the spring 43 reacts between the two plates 41 and 42 to urge them in opposite directions against the posts 35 and 36. To limit the sliding movement of post 37 a spring 44 is shown which reacts against the 95 end of member 15 and the downturned end of which is adapted to engage shoulder 39 when the post has reached the desired limit 100 of its sliding movement. The construction illustrated in Fig. 7 also permits of the 105 posts, as 35, 36, and 37, being formed in sections which are detachably connected end to end. When so constructed the lengths of the posts may be changed to accommodate a greater or less number of the sheets 14 by 110 the use of a greater or less number of the intermediate sections, as 45, in each of the 115 said posts.

Any convenient mechanism may be employed for locking the binding member 15 115 in adjusted position upon the posts 12—13 or 35—36. The arrangement illustrated in Figs. 5 and 6 comprises a longitudinally movable apertured locking plate 46 which is 120 slidably mounted within the chamber of the binding member 15 for engagement with both of the posts 12 and 13. In this instance a screw 47, having a swiveled connection, as at 48, with the locking plate 46 at one end, is employed for moving said locking plate into and out of engagement with the posts 12 and 13. Under these circumstances the adjacent end wall of the binding member 15 is provided with an aperture 49 125 in line with the screw 47 for the insertion 130

of a key (not shown) to operate the screw. In the form of construction illustrated in Fig. 7 a tilting locking plate 50 is hingedly mounted within the chamber of the binding member 15 for engagement with each of the posts 35 and 36. These locking plates are apertured to receive the corresponding post and a spring 51 serves for tilting the plate so that it will bind upon the post. A cam plate 52 is slidably mounted within the chamber of the binding member 15 for simultaneous engagement with the two locking plates 50 to lift said plates against the effort of the springs 51. The cam plate 52 is conveniently shifted by means of an eccentric 53, the stem, as 54, of which, projects through one of the side walls of the binding member 15 and is provided with a thumb piece 55, for turning the eccentric. It will be noted that the binding members 15 and 16 may be compressed upon the sheets 14 when all of the sheets have one side edge aligned with the corresponding side edges of the covers 10 and 11, as in Fig. 1, or when some of the sheets 14 have the apertures engaged with the post 21 or 37, as in Fig. 2. When the sheets are arranged as in Fig. 2 and it is desired to return those sheets which are engaged with the post 21 to the position occupied by the remaining sheets, it is only necessary to withdraw the post 21 and loosen the binding member 15 upon the posts 12 and 13. By reason of the formation of the covers 10 and 11 with their edges at one side flush with the corresponding ends of the binding members 15-16, the side edge of the ledger remote from post 21 or 37 may now be rested upon the table (not shown) and the table becomes an abutment or guide against which all of the sheets may be pressed during the return of the shifted sheets.

When the ledger is opened and placed in the rack 23, in the manner illustrated in Figs. 3 and 4, the sheets 14 are all accessible and may be separately manipulated. They are, nevertheless, guided to alignment for the subsequent insertion of the posts 12-13 or 35-36 through the apertures 19 and 20 and for the introduction of the post 21 either through the apertures 20 or beyond the adjacent edge of the sheet, by the engagement of the lower edges of the sheets with the intermediate guides 29 and 30 and by the engagement of one of the side edges of the sheet with the corresponding side guide 27 or 28. In the closed position of the ledger all of the posts 12, 13 and 21 or 35, 36 and 37 project at the same side. The closed ledger is, therefore, smooth upon one side for resting upon the table.

I claim as my invention—

1. In a ledger or the like, in combination, a pair of oppositely facing covers, and a filing post mounted for sliding movement

in the direction of its length in each of the said covers.

2. In a ledger or the like, in combination, a pair of oppositely facing equal covers, a filing post extending between the covers, and a sheet of less width than the covers punched for engagement with the filing post in more than one lateral position of the sheet between the covers, the punching of the sheet and the location of the filing post being such that in one of the positions of engagement of the sheet with the post a side edge of the sheet is in the same plane with the corresponding margins of the covers.

3. In a ledger or the like, in combination, a pair of oppositely facing covers, and a filing post mounted for sliding movement in the direction of its length in each of the said covers, one of the said posts also extending through the other cover.

4. In a ledger or the like, in combination, a pair of oppositely facing covers, a filing post mounted for sliding movement in the direction of its length in each of the said covers, one of the said posts also extending through the other cover, and means for locking the last mentioned cover to the last mentioned post.

5. In a ledger or the like, in combination, a pair of oppositely facing equal covers, a filing post extending between the covers, and a sheet of less width than the covers having a transverse slotted aperture for receiving the filing post, the length of the said slotted aperture of the sheet being greater than the width of the filing post and the locations of the said slotted aperture in the sheet and of the post in the covers being such that when the post is at one end of the slot a side edge of the sheet is in the same plane with the corresponding margins of the covers and when the post is at the other end of the slot the sheet does not extend to the said plane.

6. In a ledger or the like, in combination, a pair of oppositely facing equal covers, a filing post extending between the covers, and a sheet of less width than the covers having a transverse slotted aperture for receiving the filing post, the length of the slotted aperture of the sheet being greater than the width of the filing post and the locations of the said slotted aperture in the sheet and of the post in the covers being such that when the post is at either end of the slot the side edge of the sheet remote from such end of the slot is closely adjacent a plane passing through the corresponding side edges of the covers.

7. In a ledger or the like, in combination, a base plate, a filing post rising therefrom, and a sheet of less width than the base plate having a transverse slotted aperture for receiving the filing post, the length of the slotted aperture of the sheet being greater

85

95

100

105

115

120

125

130

than the width of the filing post and the locations of the said slotted aperture in the sheet and of the post in the covers being such that when the post is at either end of the 5 slot the side edge of the sheet remote from such end of the slot is in line with the corresponding side edge of the base plate.

8. In a ledger or the like, in combination, a pair of oppositely facing equal covers, a 10 filing post extending between the covers, and a sheet of less width than the covers punched for engagement with the filing post in two different lateral positions of the sheet between the covers, the punching of the sheet 15 and the location of the filing post being such that in the two positions of engagement of the sheet with the post the opposite side edges of the sheet are in planes closely adjacent planes passing through the corresponding side edges of the covers.

9. In a ledger or the like, in combination, a base plate, a filing post rising therefrom, and a sheet of less width than the base plate punched for engagement with the filing post 25 in two different lateral positions of the sheet upon the base plate, the punching of the sheet and the location of the filing post being such that in the two positions of engagement of the sheet with the post the opposite 30 side edges of the sheet are in line with the corresponding side edges of the base plate.

10. In a ledger or the like, in combination, a base plate, a filing post slidingly mounted in the base plate for movement through 35 the plate in the direction of the length of the post and normally projecting above the plate, and a sheet of less width than the base plate adapted for engagement with the filing post in two different lateral positions of the 40 sheet upon the base plate, the relation of the sheet to the filing post being such that in the two positions of engagement of the sheet with the post the opposite side edges of the sheet are alined with the corresponding side edges of the base plate.

11. In a ledger or the like, in combination, a pair of oppositely facing equal covers, a filing post slidingly mounted in one of the covers for movement through the same in 50 the direction of the length of the post and normally extending between the covers, and a sheet adapted for engagement with the filing post in more than one lateral position of the sheet between the covers, the relation 55 of the sheet to the filing post being such that in one of the positions of engagement of the sheet with the post a side edge of the sheet is in the same plane with the corresponding margins of the covers.

60 12. In a ledger or the like, in combination, a pair of oppositely facing equal covers, a filing post slidingly mounted in one of the covers for movement through the same in the direction of the length of the post and 65 normally extending between the covers, and

a sheet adapted for engagement with the filing post in more than one lateral position of the sheet between the covers, the relation of the sheet to the filing post being such that in the two positions of engagement of the sheet with the post the opposite side edges of the sheet are in planes lying closely adjacent to planes passing through the corresponding side edges of the covers.

70 13. In a ledger or the like, in combination, a base plate, a filing post rising therefrom and a sheet of less width than the width of the base plate adapted for engagement with the filing post in two different lateral positions of the sheet upon the base plate, the relation of the sheet to the post being such that in the two positions of engagement of the sheet with the post the opposite side edges of the sheet are alined with the corresponding side edges of the base plate and an end of the sheet is alined with the corresponding end of the base plate.

75 14. In a ledger or the like, in combination, a base plate, a filing post slidingly mounted in the base plate for movement through the plate in the direction of the length of the post and normally projecting above the plate, and a sheet of less width than the base plate adapted for engagement with the post when either side edge of the sheet is alined with the corresponding side edge of the base plate and an end of the sheet is alined with the corresponding end of the base plate.

80 15. In a ledger or the like, in combination, a pair of equal covers, two filing posts between the covers and sheets of less width than the covers having punch holes for receiving both of the posts when the edges of the sheets at one side are in the same plane with the corresponding margins of the covers and for receiving one of the posts when the said edges of the sheets are engaged with the other post and the opposite edges of the sheets are in the same plane with the corresponding margins of the covers.

85 100 16. In a ledger or the like, in combination, a pair of equal covers, two filing posts slidingly mounted in the covers for movement in the direction of the length of the posts and normally extending between the covers, and sheets of less width than the covers having punch holes for receiving both of the posts when the edges of the sheets at one side are in the same plane with the corresponding margins of the covers and for receiving one of the posts when the said edges of the sheets are engaged with the other post and the opposite edges of the sheets are in the same plane with the corresponding margins of the covers.

90 105 110 115 120 125 130 17. In a ledger or the like, in combination, a pair of covers having alined side edges, two relatively offset filing posts each slidingly mounted in one of the covers for

movement through the cover in the direction of the length of the post and both of the posts normally extending between the covers, and sheets of less width than the covers 5 having punch holes for receiving both of the posts when the edges of the sheets at one side of the same are in the same plane with the corresponding side edges of the covers and for receiving one of the posts when the 10 said edges of the sheets are engaged with the other post and the opposite edges of the sheets are in the same plane with the corresponding margins of the covers.

18. In a ledger or the like, in combination, a pair of covers having alined margins at one side and at one end, a filing post mounted in one of the covers and extending toward the other cover, sheets having punch holes for receiving the filing post when one 20 side edge and an end of each sheet are alined with the said two margins of the covers, and a rack comprising a pair of oppositely facing sloping supports for the covers when separated a greater distance than the length of 25 the said filing post and a pair of guides extending between the said supports and alined respectively with the said side and end margins of the covers.

19. In a ledger or the like, in combination, a pair of covers having alined margins at one side and at one end, a filing post slid-

ingly mounted in one of the covers for movement through the same in the direction of the length of the post and normally extending toward the other cover, sheets having 35 punch holes for receiving the filing post when one side edge and an end of each sheet are alined with the said two margins of the covers, and a rack comprising a pair of oppositely facing sloping supports for the covers 40 and a pair of guides extending between the said supports and alined respectively with the said side and end margins of the covers.

20. In a ledger, or the like, in combination, a 45 pair of covers having alined margins at their two sides and at one end, a filing post extending between the covers, a sheet of less width than the covers punched for engagement with the filing post when the end of the 50 sheet is alined with the said end margins of the covers and when either side edge of the sheet is alined with portions of the corresponding side margins of the covers, and a rack comprising a pair of oppositely facing 55 sloping supports for the covers and a plurality of guides extending between the said supports, the said guides being alined respectively with portions of the two side margins and with the said end margins of 60 the covers.

JAMES C. DAWSON.
